UNITED STATES PATENT OFFICE.

ELIE W. LABOMBARDE, OF NASHUA, NEW HAMPSHIRE.

WET PRESS.

Application filed February 16, 1920. Serial No. 358,981.

To all whom it may concern:

Be it known that I, ELIE W. LABOMBARDE, a citizen of the United States, and resident of Nashua, in the county of Hillsborough 5 and State of New Hampshire, have invented a new and useful Wet Press, of which the following is a specification.

The principal object of my invention is to provide a machine which will efficiently remove water from pulp with the consequent improvement of the product and reduction of its volume, the latter reducing freight charges for transportation.

Another object is to exert a powerful and 10 positive pressure on the material.

Another object is to do away with the felt carrier heretofore used with the result that I save the cost of the felt itself which is not only expensive but is not durable and I also 20 save practically the entire expense of an attendant because heretofore each press has required an attendant to scrape off the material and to adjust the felt which tends to work out of alignment.

25 A feature of my invention is pressing mechanism which acts independently of the conveying mechanism and in the preferred form the pressure is positive and the pressing mechanism is stationary with relation 30 to the direction of the feed of the material.

Another feature consists in pressing mechanism which includes a reciprocating member.

The mechanism for delivering the material to the positive press and for removing it therefrom are also important features of 35 my invention.

Other features will be pointed out below.

In the drawings—

40 Figure 1 is a plan of a machine embodying my invention;

Figure 2 is an elevation of the same;

Figure 3 is an elevation of the other side of said machine;

45 Figure 4 is a section on line 4—4 of Figure 1;

Figure 5 is a sectional view on line 5—5 of Figure 4;

50 Figure 6 is a partial elevation showing the operating mechanism for the movable bed member;

Figure 7 is a section on line 7—7 of Figure 4;

55 Figure 8 is a sectional detail on line 8—8 of Figure 7;

Figure 9 is a partial elevation of a modification of the pressing mechanism; and

Figure 10 is a detail of part of the bed operating mechanism of said modification.

Upon the bed or support A is suitably 60 mounted the frame which comprises the receptacle part A', the supporting part A² and the intermediate part A³, these parts being rigidly connected to each other and supporting the various elements hereinafter 65 described.

The material, which may be pulp with a considerable amount of water, is delivered to the receptacle at the mouth a and passes through opening a' beneath wall a² which 70 extends clear across the receptacle.

Within the receptacle is suitably mounted roll B whose surface is of wire cloth b, the shaft b' of said roll extending through one side wall of the receptacle and having fixed 75 to it gear b² meshing with gear b³ fixed on shaft b⁴, the latter being fixed to gear b⁵ meshing with gear b⁶ fixed to shaft b⁷ suitably connected to the source of power.

Roll D whose surface is of canvas d or 80 felt or other suitable material is fixed to shaft d' mounted on arm d² pivoted to bracket d³ and on arm d⁴ pivoted to bracket d⁵, the arms being connected by cross-bar d⁶. Springs d⁷ and d⁸ tend to pull said arms 85 downwardly and thereby hold roll D in proper relation to roll B so that the latter, which picks up the material within the receptacle, will force the material against roll D, rotating the latter which carries with it 90 the material and I preferably remove more of the water by using roll E which is spring-pressed against roll D, said roll E being mounted on a shaft carried by arm e pivoted to arm d² and by arm e' pivoted to arm d⁴. 95 Spring e² is connected to pin e³ on arm d² and to arm e to draw the latter toward roll D and I use a similar spring e⁴ for arm e'.

The material carried around by roll D is scraped off by a scraping carrier F which 100 extends across the roll D substantially throughout its length, said carrier comprising a scraping edge f carried by arms f' which are rigidly connected to shaft f² which is mounted to oscillate in bearing f³ at one side of the machine and in bracket f⁴ at the other side of the machine, said shaft being provided outside of said bracket with a gear f⁵ meshing with sector gear f⁶ whose shaft f⁷ 105 is mounted on said bracket, said shaft f⁷ 110

carrying also cam arm f^8 which has a headed pin f^9 engaged by the end f^{10} of a coiled spring f^{11} also mounted on said bracket, said end f^{10} normally holding said cam arm in its lower position as shown in Figure 3 and consequently holding the edge f of the scraping carrier in engagement with roll D. Said carrier is moved away from said roll and carries the material onto the bed of the press by mechanism hereinafter described which acts on the peripheral surface of said cam arm.

When carrier F is substantially covered by the material which it has scraped from roll D it is swung over (by mechanism described below) and lays the material on fixed perforated bed G and on movable perforated members G' and G², bed G being slotted at g to receive arms g'. The fixed bed has fixed walls g^2 , g^3 , g^4 and vertically reciprocating front wall G^5 having slots g^5 and g^6 to permit swinging movement of arms g'. When the material has been deposited on members G, G' and G², the last two-mentioned members are swung upwardly and inwardly to fold over the ends of the sheet of material onto the central portion, shaft g^8 having fixed connection with member G² and carrying gear g^9 meshing with sector g^{10} which carries a pin g^{11} connected to spring g^{12} . Sector g^{13} is operated by sector g^{10} and actuates gear g^{14} fixed on shaft g^{15} which is fixed to member G', sector g^{13} being mounted on shaft g^{16} which has a lug g^{17} actuated by cam g^{18} on shaft h^9 . The members G' and G² are swung back to normal position by spring g^{12} and then movable press member H moves down, said member H being mounted on rod h which extends across the machine and has near its ends rectangular blocks h^1 , h^2 to ride in guides h^3 and h^4 , the ends of rod h being pivotally connected with connecting rods h^5 and h^6 , and these being operated by cranks h^7 and h^8 connected to opposite ends of shaft h^9 , which near one end carries gear h^{10} meshing with gear h^{11} , the latter being carried by shaft h^{11} carrying pulley h^{12} connected by belt h^{13} with pulley h^{14} on shaft h^{15} which carries pulley h^{16} connected by belt h^{17} with pulley h^{18} on the power shaft. The connecting rod h^5 carries a pin h^{19} which engages the cam surface of member f^8 to swing the carrier F toward bed G and when the carrier has reached the end of its travel pin h^{19} enters notch f^{13} whereupon spring f^{11} acts to give an upward jerk to carrier F which efficiently separates the material from the carrier and then the spring f^{11} acts to return the carrier to its starting position, the cam surface of member f^8 permitting this return gradually.

The member H gives a positive pressing action on the material to remove the water and when it is raised sufficiently the front

wall G^3 of the press moves down in guides G^4 and G^5 , member G^3 carrying pin G^6 engaging in slot G^7 of arm G^8 which is pivoted to shaft G^9 , arm G^8 being moved down by dog G^{10} fixed to shaft G^9 said dog being actuated by cam G^{11} on shaft h^9 . When wall G^3 has moved down sufficiently the material is removed from bed G by the arms g' and then spring G^{13} returns wall G^3 to normal position.

The arms g' are fixed to shaft G^{14} which carries gear G^{15} meshing with sector G^{16} oscillated in one direction by cam G^{17} on shaft h^9 acting on portion G^{18} and in the other direction by spring G^{19} .

The arms g' lay the material on travelling apron K carried by pulleys K' and K² the shaft of the latter carrying pulley K³ connected by cross belt K⁴ to pulley K⁵ on shaft h^{15} .

Apron K conveys the material to perforated metal roll L which carries it along between said roll L and another perforated metal roll L' which exert great pressure on the material and feed it between fixed plate L² and plate L³, the latter being pivoted and normally held up in engagement with roll L' by coiled springs L⁴ and L⁵. Passing out between plates L² and L³ the material is carried off by belt L⁶. The roll L is a floating roll actuated by roll L⁶ which is mounted on shaft L⁷ carrying gear L⁸ meshing with pinion L⁹ on shaft h^{15} while L' is also a floating roll held in place by roll L¹⁰ whose shaft L¹¹ is mounted in bearing blocks L¹² and L¹³ mounted to move on guides L¹⁴ and L¹⁵ and adjusted for the desired pressure by coiled springs L¹⁶ and L¹⁷.

In using my machine the material, which contains a relatively large amount of water, is fed into the receptacle and is carried up by roll B and between rolls B and D which squeeze out some of the water the axes of these rolls being relatively offset to better pick up the material. The material is then carried around by roll D and more water is squeezed out between rolls D and E, the material being carried around by roll D to the scraping carrier F, by which the material is scraped off until it substantially covers said carrier, which is then swung so as to lay the cake or sheet of material on members G, G' and G², the carrier being given a slight spring jerk upward as described to more effectually remove the material, the carrier then returning to its original position to scrape off more material. The next step is the bending over of the ends of the sheet by members G' and G² so that all the material is within the walls of the fixed bed G, the members G' and G² then returning to normal position. Thereupon the member H is brought down into engagement with the material and exerts a very powerful and positive pressure which removes the water and

renders the material of the desired consistency, the material being at this time stationary with relation to the direction of the feed. The member H is then moved up, 5 wall G³ is moved down and the arms g' lift the sheet from bed G and, swinging over, lay the sheet on apron K which conveys the material to the rolls L and L' which, by reason of their mounting, give a pulling or 10 sweeping action to the material which is conveyed between plates L² and L³ to removing belt L⁶.

In Figures 9 and 10 I show a modification of the positive press and of the carrying 15 mechanism thereto and therefrom. In this modification the rolls M and M' are similar to rolls B and D, roll M' however being fixed to shaft m which is journaled in blocks m' (one being shown), said block being adjustable by hand wheel m². The scraping member M² is fixed and leads to curved member M³. Sprockets M⁴ and M⁵ (and others not shown) actuate belt M⁶ which is provided with dogs or dams M⁷ which move 20 the material along members M² and M³ into position on movable press member M⁸ which is flush with the top of member M² when the material is moved onto it, member M⁸ being moved by arms M⁹ and M¹⁰ pivoted at 25 M¹¹ and pivotally connected to arms M¹² and M¹³ which are operated by cam M¹⁴ on the main shaft. When the material has been moved onto M⁸ the latter is moved down into the position in Figure 10, so that 30 the top of member M⁸ forms the bottom of a pressing chamber, two walls of which are provided by members M³ and M¹⁵, two other walls (not shown) being also provided. Thereupon the other press member M¹⁶ is moved down to give positive pressure to the material, member M¹⁶ being mounted in guides such as M¹⁷ and being actuated by connecting rod M¹⁸ pivotally connected to wheel M¹⁹ mounted on the main 35 shaft. When the pressing has been done the member M¹⁶ is raised and member M⁸ is moved up until its top is flush with members M³ and M¹⁵ whereupon the belt M⁶ is actuated and the dogs M⁷ move the material 40 along flat member M¹⁵ and on to travelling apron M²⁰ which conveys the material to the desired location for removal. It will be understood that the movement of belt M⁶ is intermittent and that two belts are provided, one at each side of the pressing chamber so that they will not interfere with the pressing, the dogs M⁷ extending across the machine from one belt to the other.

I have also provided a bracket comprising 45 two arms N and N' and cross bar N² upon the latter of which is pivotally mounted sleeve N³ having integral therewith the depending arms N⁴ N⁵ curved at their lower ends, said sleeve being held in place

by collars n and n' pinned to the cross bar 65 N².

As the arms g' carry the material over onto apron K the arms N⁴ and N⁵ are swung toward roll L' to permit the material to be placed on apron K but as the material is so placed the arms N⁴ and N⁵ swing back to their vertical position so as to ensure separation of said material from arms g' when the latter are swung back to bed G, that is to say, arms N⁴ and N⁵ make sure that the material will remain on apron K, arms N⁴ and N⁵ being so located transversely of the machine that they will not interfere with the return movement of arms g'.

What I claim is:

1. A machine of the character described comprising positive pressing mechanism; means to deliver portions of the material separated from each other to said mechanism, said mechanism acting upon each portion 85 with relation to the direction of the delivery to said mechanism; and means to deliver the material from said mechanism.

2. A machine of the character described comprising means to remove water from the material; positive pressing mechanism; means to deliver portions of the material separated from each other from said means to said pressing mechanism, said mechanism 95 acting upon each portion while said portion is stationary with relation to the direction of delivery to said mechanism; and means to convey the material from said pressing mechanism.

3. A machine of the character described comprising positive pressing mechanism including a reciprocating member; means to deliver portions of the material separated from each other to said mechanism, said 105 mechanism acting upon each portion while such portion is stationary with relation to the direction of the delivery to said mechanism; and means to deliver the material from said mechanism.

4. A machine of the character described comprising positive pressing mechanism including a permanently fixed member in direct contact with the material and a cooperating reciprocating member; means to carry 115 separated portions of the material to said mechanism; and means to deliver the material from said mechanism.

5. A machine of the character described comprising a pressing chamber having permanently fixed walls; movable mechanism cooperating with said walls to press the material; means to carry separate portions of the material within said walls; and means to remove the material from within said 125 walls.

6. A machine of the character described comprising positive pressing mechanism

- which is permanently stationary with relation to the direction of feed of the material; means to carry separated portions of the material to said mechanism; and means to deliver the material from said mechanism.
7. A machine of the character described comprising pressing mechanism; and pivoted carrying means to carry the material to said mechanism by swinging on its pivot.
- 10 8. A machine of the character described comprising pressing mechanism; and oscillating carrying means to carry the material to said pressing mechanism.
- 15 9. A machine of the character described comprising positive pressing mechanism; and oscillatory carrying means to carry the material to said pressing mechanism.
- 20 10. A device of the character described comprising rolls to remove water from the material; pressing mechanism; and oscillatory means to carry the material from said rolls to said pressing mechanism.
- 25 11. A device of the character described comprising rolls to remove water from the material; positive pressing mechanism; and oscillatory means to carry the material from said rolls to said pressing mechanism.
- 30 12. A device of the character described comprising a receptacle for the material; means to remove the material from said receptacle; and means to scrape the material from said removing means; and means to move said scraping means.
- 35 13. A device of the character described comprising a receptacle for the material; means to remove the material from said receptacle; a member having an edge to scrape the material from said removing means and having a perforated body; and means to move said member.
- 40 14. A device of the character described comprising a receptacle for the material; means to remove the material from said receptacle; a member having an edge to scrape the material from said removing means; and means to oscillate said member.
- 45 15. A device of the character described comprising means to press the material; and oscillating means to deliver the material to said pressing means including provision for giving a quick partial reverse movement to said oscillating means just after the latter has brought the material to said pressing means.
- 50 16. A device of the character described comprising means to press the material; an oscillatory member to receive the material and deliver it to said pressing means; means including a cam surface with an indentation to move said oscillatory member in one direction to deliver the material; and resilient means acting to return the oscillatory member to its receiving position and also acting in cooperation with said indentation to give a quick partial return
- movement to said member for the purpose of snapping said member away from the material.
17. A machine of the character described comprising positive pressing mechanism including a permanently fixed member in direct contact with the material; a cooperating reciprocating member and means to reciprocate the latter member; means to carry separated portions of the material to said mechanism; and means to remove the material from the pressing mechanism.
- 70 18. A machine of the character described comprising pressing mechanism including a permanently fixed member in direct contact with the material, a reciprocating member and means to positively move the latter member toward the fixed member; means to carry separated portions of the material to said mechanism; and means to remove the material from the pressing mechanism.
- 80 19. A machine of the character described comprising a fixed press member; two pivoted members, one at each side of said press member, the pivoted members being normally substantially flush with said fixed member; means to deposit the material on said fixed and pivoted members; means to swing the pivoted members to deposit the end portions of the material over said fixed bed; and movable means to cooperate with the fixed bed to press the material when the ends have been so deposited.
- 85 20. A machine of the character described comprising a fixed bed having openings; a pivoted member having arms to rest normally in said openings; a movable press member to press the material against said bed and said arms; means to operate the movable member; and means to swing said pivoted member to carry the material away from said bed.
- 90 21. A machine of the character described comprising a fixed bed having openings; a wall adjacent to said bed and having openings; a pivoted member having arms normally extending through the openings in said wall and resting in the openings in said bed; a movable press member; means to move said press member into co-operative relation with said wall and with said fixed bed; means to move said wall out of operative position; and means to swing said pivoted member to carry the material away from said bed.
- 95 22. A machine of the character described comprising pressing mechanism; and pivoted carrying means to remove the material from said mechanism by swinging on its pivot.
- 100 23. A machine of the character described comprising positive pressing mechanism; and pivoted carrying means to remove the material from said mechanism by swinging on its pivot.
- 105 115 120 125 130

24. A machine of the character described comprising pressing mechanism; and oscillatory carrying means to remove the material from said mechanism.
- 5 25. A machine of the character described comprising positive pressing mechanism; and oscillatory carrying means to remove the material from said mechanism.
- 10 26. A machine of the character described comprising cooperating rolls to remove water from the material; pressing mechanism; oscillatory means to convey the material from one of said rolls to said pressing mechanism; and oscillatory means to remove the material from said pressing mechanism.
- 15 27. A machine of the character described comprising cooperating rolls to remove water from the material; pressing mechanism; an oscillatory member to convey the material from one of said rolls to said pressing mechanism and having an edge to remove the material from said one roll; and oscillatory means to remove the material from said pressing mechanism.
- 20 28. A machine of the character described comprising cooperating rolls to remove water from the material; pressing mechanism; oscillatory means to convey the material from one of said rolls to said pressing mechanism; and an oscillatory member to remove the material from said pressing mechanism and extending beneath the material during the pressing.
- 25 29. A machine of the character described comprising cooperating rolls to remove water from the material; pressing mechanism including a reciprocating member; oscillatory means to convey the material from one of said rolls to said pressing mechanism; and oscillatory means to remove the material from said pressing mechanism.
- 30 30. A machine of the character described comprising cooperating rolls to remove water from the material; pressing mechanism including a reciprocating member; an oscillatory member to convey the material from one of said rolls to said pressing mechanism and having an edge to remove the material from said one roll; and oscillating means to remove the material from said pressing mechanism.
- 35 31. A machine of the character described comprising cooperating rolls to remove water from the material; pressing mechanism including a reciprocating member; oscillatory means to convey the material from one of said rolls to said pressing mechanism; and an oscillatory member to remove the material from said pressing mechanism and extending beneath the material during the pressing.
- 40 32. A machine of the character described comprising cooperating rolls to remove water from the material; pressing mechanism; an oscillatory member to convey the material from one of said rolls to said pressing mechanism and having an edge to remove the material from said one roll; and oscillating means to remove the material from said pressing mechanism.
- 45 33. A machine of the character described comprising cooperating rolls to remove water from the material; pressing mechanism including a reciprocating pressing member; an oscillatory member to convey the material from one of said rolls to said pressing mechanism and having an edge to remove the material from said one roll; and an oscillatory member to remove the material from said pressing mechanism and extending beneath the material during the pressing.
- 50 34. A machine of the character described comprising two shafts; a roll mounted on each shaft; means to drive one of said rolls; two hollow rolls, each enclosing one of said mounted rolls and being of larger diameter than the mounted roll which it encloses, said hollow rolls acting on the material.
- 55 35. A machine of the character described comprising two shafts; a roll mounted on each shaft; means to drive one of said rolls; two hollow rolls, each enclosing one of said mounted rolls and being of larger diameter than the mounted roll which it encloses, said hollow rolls acting on the material; and means to relatively adjust the rolls.
- 60 36. A machine of the character described comprising two shafts; a roll mounted on each shaft; means to drive one of said rolls; two hollow metal perforated rolls, each enclosing one of said mounted rolls and being of larger diameter than the roll it encloses, said hollow rolls acting on the material.
- 65 37. A machine of the character described comprising a receptacle for the material; a roll to remove the material from the receptacle; a second roll cooperating with the first roll to remove water from the material; and a third roll cooperating with the second roll to remove water from the material; and resilient means to hold the third roll in cooperative relation to the second roll.
- 70 38. A machine of the character described comprising two relatively movable cooperating plates to engage the material; and means to feed the material between said plates while they are in engagement with the material.
- 75 39. A machine of the character described comprising a fixed plate; a movable plate; resilient means for holding the movable plate normally in the desired position; and means to feed the material between said plates.
- 80 40. A machine of the character described comprising pressing mechanism; means to receive the material; oscillatory means for

delivering the material from the pressing mechanism to the receiving means; and pivoted means to cooperate in said delivery of the material.

5 41. A machine of the character described comprising pressing mechanism; means to receive the material; oscillatory means for delivering the material from the pressing mechanism to the receiving means; pivoted means to cooperate in said delivery of the material; and a spring to hold said pivoted means normally in the desired position.

10 42. A machine of the character described comprising a moving apron; pressing mechanism; means to deliver portions of the material separated from each other to said pressing mechanism; and means to convey the material from said mechanism to said apron.

15 43. A machine of the character described comprising a moving apron; pressing mech-

anism; means to deliver portions of the material separated from each other to said pressing mechanism; and oscillatory means to convey the material from said mechanism to said apron. 25

44. A machine of the character described comprising pressing mechanism; a carrier; means to convey the material from said mechanism to said carrier; and means to ensure removal of the material from said conveying means. 30

45. A machine of the character described comprising pressing mechanism; a carrier; means to convey the material from said mechanism to said carrier; and pivoted means normally in position to ensure removal of the material from said conveying means but mounted to permit movement of the material toward said carrier. 35

ELIE W. LABOMBARDE.
